BINDING ARRANGEMENT

John Francis Russell, North Arlington, N. J.

Application January 10, 1938, Serial No. 184,116

3 Claims. (Cl. 129—1)

This invention relates to leaf-retaining devices and provides a leaf-retaining device which is particularly suitable for fabrication from fibrous cellulosic sheet material such as laminated sheets of so-called "fibre" made by consolidating a plurality of juxtaposed sheets of cellulosic material treated with zinc chloride or other reagent which causes the cellulose fibres to alter, thus adding strength, hardness and resilience to the mass. The fibre best adapted to the manufacture of the leaf-retaining device of my invention is made by impregnating cotton rag stock with a relatively concentrated aqueous solution of zinc chloride, wrapping the stock in sheet form around a cylinder of large diameter to form a laminated annular mass about .04 inch in thickness or say twice that desired in the final product. The laminated annular mass is cut and stripped from the cylinder as a sheet, and washed in a series of aqueous zinc chloride baths of diminishing concentration and finally with water alone. The washed sheet is then dried and pressed flat to facilitate handling. During drying the sheet shrinks considerably in all directions and becomes a strong mass about .02 inch thick.

A sheet thus produced has physical properties which are entirely different from those of Celluloid and similar materials heretofore employed in the manufacture of leaf-retaining devices. The resilience of the sheet is considerable although less than that of Celluloid. Its surface is less smooth than that of Celluloid sheet and hence offers a greater frictional resistance. It can be bent readily in a relatively sharp angle or curve without breaking, whereas Celluloid and the like tends to crack under similar treatment. Moreover, it has a high resistance to fatigue through flexure and may be bent repeatedly in a sharp curve or angle without breaking; under like treatment Celluloid will crack. Because of its somewhat fibrous character, the sheet may be made to adhere firmly to other fibrous surfaces through the use of various forms of cementing agents. Because of its yieldable character the sheet does not tend to break away from a surface to which it has been cemented, even under considerable flexure. Moreover, the sheet is relatively cheap and easily worked.

Because of its peculiar physical properties, the "fibre" sheet does not form satisfactory leaf-retaining devices of the type heretofore fabricated from Celluloid and similar resilient "plastics". However, as a result of my investigations, I have developed a type of leaf-retaining device which is well suited for manufacture from

fibre and results in an inexpensive, durable and convenient binding of attractive appearance. Accordingly, my invention contemplates a leaf-retaining device which comprises an integral sheet of fibrous resilient material having an elongated substantially flat back, a plurality of long teeth formed integrally with the back and projecting relatively sharply from one edge of the back and curved less sharply inwardly toward the back with their free ends abutting the back adjacent the opposite edge thereof, and a plurality of short teeth matching the long teeth formed integrally with the back and projecting relatively sharply from said opposite edge of the back and curved inwardly toward the back so that they overlap the respective long teeth. In a preferred form of the structure according to my invention, the leaf-retaining device is fastened inside a folder with the flat back cemented or otherwise fastened to a back member of the folder between a pair of integrally formed overlapping covers. These and other features of my invention will be more clearly understood in the light of the following detailed description taken in conjunction with the accompanying drawing, in which:

Fig. 1 illustrates a preferred form of the leaf-retaining device of my invention; and

Fig. 2 illustrates an assembly in which the leaf-retaining device is placed within a folder.

Referring now to the drawing, it will be seen that the leaf-retaining device comprises an elongated, substantially flat back 10 made of fibrous, resilient material (preferably from "fibre" of the variety described hereinbefore), a plurality of long teeth 11, 12, 13, formed integrally with the back and projecting therefrom through a relatively sharp curve or angle 14. The long teeth extend through a more gradual curve to the opposite edge of the flat back and substantially abut thereto.

Overlapping the respective long teeth are a plurality of short teeth 15, 16, 17, which are formed integrally with the flat back and project from the edge thereof opposite the edge to which the long teeth are fastened. The short teeth also project from the flat back through a relatively sharp curve or angle 18, but are less sharply curved throughout most of their length, so that they fit against the outside of and retain the loose ends of the long teeth.

The teeth preferably are relatively wide, say $\frac{1}{4}$ inch, when the thickness of sheet from which they are made is about $\frac{1}{100}$ of an inch. In such circumstances the teeth should be spaced on

about $\frac{1}{2}$ inch centers so that the gap between the teeth is substantially of the same width as the teeth.

Leaves 23 to be retained by the device have rectangular holes 24, 25, 26 in them through which the long teeth may be projected. In fastening leaves into the retaining device, the long teeth are pulled out of engagement with the short teeth far enough to leave a gap through which the leaves may be inserted. After the leaves are inserted, the long teeth are permitted to resume their position inside the short teeth. This is facilitated by bending the short teeth slightly outward. Because of the relatively sharp angle which the teeth make with the back member, the long teeth tend to push outwardly against the short teeth when a pull is exerted upon them. This increases the friction between the teeth and hence increases the security with which the leaves are retained in the device. The relatively sharp curve or angle with which the teeth meet the back member is particularly desirable because of the nature of the material which tends to act as a hinge at the point where the teeth are joined to the back in preference to bending through the length of the teeth.

Referring now to Fig. 2, it will be seen that the binding element of Fig. 1 is fastened (preferably with some cementing agent such as glue) to the inside of a flat folder back 19 which is substantially the same width as the back of the leaf-retaining device, but slightly longer. The back of the leaf-retaining device may be fastened to the folder back by means of rivets (not shown), but ordinarily the best course is to employ a cementing agent. Formed integrally with the back of the folder and bent so as to overlap the leaf-retaining device are a pair of covers 20, 21 which overlap the leaf-retaining device and protect the retained leaves.

In manufacturing the leaf-retaining device of my invention, the fibre described hereinbefore is cut into the desired flat shape, moistened with water, and bent over a mandrel or other form to conform to the shape shown in Fig. 1. The moistened fibre is then dried on the form. Efforts to dry the moistened leaf-retaining device while unsupported will usually be unsatisfactory because warping and distortion tend to occur.

When the leaves have been inserted in the finished leaf-retaining device, they will be held securely thereby because of the tendency of the long teeth to force outwardly against the short teeth, this being the result of hinge effect at the point where the long teeth fasten to the back. Consequently, it is unnecessary to apply any cementing agent to hold the teeth together, and leaves may be withdrawn and reintroduced many times without exhausting the resilient hinges at the points 14, 18.

To assure that the teeth are locked together in

an adequate manner, it is desirable in some instances, and particularly when the resilient fibrous material from which the leaf-retaining device is made has an exceptionally smooth surface, to upset a portion of both long teeth and short teeth where they overlap so that a depression is formed on either the long tooth or the short tooth and a corresponding nub or projection is formed on the other tooth and fits into the depression. The depression and projection may be formed conveniently while the material is moist, simply by pressing a hard round instrument against the overlapping teeth. In Fig. 1, depressions 27 are shown punched into the outer surface of short teeth 15, 17, respectively, so that on the inner portion of these short teeth there are corresponding projections. Similarly, on the inner surface of the overlapped long teeth 11, 13, depressions are formed into which the projections on the short teeth fit. A similar result is obtained with the teeth 16, 12, by upsetting the two from the inside, so that a projection 28 is formed on the upper surface of the tooth 16, a corresponding projection on the tooth 12 fitting into the resulting depression on the lower surface of the tooth 16.

I claim:

1. A leaf-retaining device which comprises an integral sheet of fibrous resilient material having an elongated substantially flat back, a plurality of short curved teeth spaced along and projecting relatively sharply from one side of said back, and a plurality of matching long curved teeth spaced along and projecting relatively sharply from the other side of said back, the long teeth extending in a less sharp arc to the opposite side of the flat back and abutting substantially perpendicular thereto, with the short teeth overlapping and fitting against the outer surfaces of the respective matching long teeth.

2. A leaf-retaining device which comprises an integral sheet of fibrous resilient material having an elongated substantially flat back, a plurality of long teeth formed integrally with the back and projecting relatively sharply from one edge of the back and curved less sharply but inwardly toward the back throughout most of their length with their free ends substantially abutting the back adjacent the opposite edge thereof and substantially perpendicular thereto, and a plurality of short teeth matching the long teeth, said short teeth being formed integrally with the back and projecting relatively sharply from said opposite edge of the back and curved less sharply but inwardly toward the back throughout most of their length so that they overlap and fit against the respective long teeth.

3. Apparatus according to claim 2 in which the distance between centers of the teeth is approximately twice the width of the teeth.

JOHN FRANCIS RUSSELL
